UNITED STATES PATENT OFFICE.

FREDERICK W. C. NEUNER, OF CONNERSVILLE, INDIANA, ASSIGNOR TO INDIANA LAMP CORPORATION, OF CONNERSVILLE, INDIANA, A CORPORATION.

LAMP CONSTRUCTION.

Application filed May 28, 1927. Serial No. 195,034.

This invention relates to a lamp construction.

The chief object of the invention is to simplify and improve a head lamp construction, particularly the arrangement whereby the reflector, lens closure and door rim are all rigidly mounted within or upon the casing.

The chief feature of the invention consists in the provision of a lens supporting ring, associated with which is a U-shaped clamping member which clampingly engages a portion of the closure or door rim for retaining the lens closure in abuttable relation with the clamping ring and in centered relation thereto.

The full nature of the invention will be understood from the accompanying drawings and the following description and 20 claims:

In the drawings Fig. 1 is an enlarged central sectional view of the invention. Fig. 2 is a plan view of a portion of the lens, its support and the clamping mechanism associated therewith, the same being taken in the plane of 2-2 of Fig. 1 with the door rim or lens retainer removed. Fig. 3 is a central sectional view of the bearing ring.

In the drawings 10 indicates the casing 30 of a head lamp construction closed by a door rim 11 which is telescopically associated therewith. Said door rim is extended rearwardly at 12 and a forward inner extension 13 forms an annular groove receiving portion and therebetween in clamped relation is a bearing ring 14, the same having a curled or beaded forward portion 15 for seating or nesting in the grooved portion 16 of the door rim. Said bearing ring at diametrical points is relieved or offset by inclined portions 17 and a parallel flange 18. A U-shaped retainer having a central portion 19 in the arms 20 is adjustably mounted within the casing by an exteriorly exposed adjusting member in the form of a screw bolt 21. The free end of the U-shaped clamping member is extended forwardly at 22 and laterally and outwardly as at 23 to bear against the face portion 18 45 of the bearing ring for retaining the rim or door closure in telescopic position upon the casing.

Inward movement of the door rim is opposed by the same bearing on the lens closure 24, which in turn bears upon a clamping

ring 25 which has a ridge or arcuate portion 26 for centering said lens closure and extending therefrom is a bearing portion 27 that bears upon the free and open end of the casing, such bearing being enclosed by 60 the door rim. The clamping ring 25 is slotted at diametrical points 29 and through said slotted portions extend the free ends 22 of the U-shaped clamping member. Thus, clamping action tending to telescope the rim upon the casing is opposed by the lens closure bearing on the clamping ring 25 which bears upon the end of the casing. Rigid with the clamping ring is a reflector 30 associated with which is a light bulb receiving 70 socket 31 and the usual light bulb 32. The resultant construction is a relatively rigid arrangement consisting of but a relatively few parts and these of simple formation.

The invention claimed is:

1. In a head lamp construction, the combination of a casing, a reflector mounted therein and including an outwardly extending portion formed for lens closure engagement and positioning and for casing engagement, a lens closure, a door rim bearable thereon, an anchoring ring carried by the rim and including a plurality of offset socket and bearing portions arranged in spaced relation, a clamping means between said casing and reflector and having a free end seatable in each socket and bearing on same for securing the reflector and closure within and upon said casing, and a single means extending into the casing and engaging the clamping means for securing the free ends in bearing relation in said sockets.

2. In a lamp construction, the combination of a casing, a reflector bearing thereon, a lens closure bearing thereon, a door rim for the casing bearing on the closure, a ring rigid with the rim and including a plurality of offset socket portions arranged in spaced relation about the ring for anchoring and clamping engagement, clamping means having a free end seatable in each of said socket portions and engaging the same for clampingly mounting the rim, and a tongue and groove connection between said rim and ring for centering and securing the same.

3. In combination, a casing, a lens closure therefor, a reflector in the casing engageable by the closure, a door rim engaging one face of the closure and telescoping the casing, a clamping and centering ring inter-

posed between the reflector and the closure and including a plurality of spaced apertures, a bearing ring supported within said door rim and including a plurality of offset 5 portions arranged in spaced relation about the ring, each forming a socket adjacent the first-mentioned ring aperture, means having a free end extending through each aperture and receivable by the adjacent socket

and bearable thereon for securing the closure 10 to the rim, and a tongue and groove connection between the bearing ring and the rim for securing the same together in centered relation.

In witness whereof, I have hereunto af- 15 fixed my signature.

FREDERICK W. C. NEUNER.
